MACHINE FOR BACKFILLING TRENCHES

William E. Burkholder, Bluffton, Ohio

Application January 17, 1949, Serial No. 71,334

2 Claims. (Cl. 37—144)

1

The invention to which the following specification relates is in an improved machine for back-filling trenches. In general it is intended to replace the dirt which has been excavated in making a trench of indeterminate length. Such an operation is commonly carried out whenever it is desired to lay pipes, drain tile, cables or the like.

In such an operation, the dirt which has been removed from a trench is ordinarily piled in the form of a narrow ridge on one side of the trench. After the pipes, cables or the like have been laid in the open trench, this dirt must be replaced to fill the trench. It has been known to provide means by which this general purpose can be accomplished. My invention is characterized by a machine which can be incorporated in a wheel tractor of the usual type. The machine is then operated by power from the tractor and, as the latter is advanced slowly, serves to spade the material from the ridge into the open trench until the latter has been filled up.

In carrying out such a routine, it is essential that all of the loose dirt shall be scraped up and brought within the field of action of the spades themselves. At the same time, means must be provided to prevent the dirt from being scattered or thrown beyond the open trench with the incidental burden of cleaning up.

One of the objects of my invention is to provide simple and effective means for rapidly back-filling an open trench in which operation the machine is automatically guided or directed along the trench for its filling.

A further object of my invention is to provide for uniform and equal adjustment of the minimum height of the spade elements throughout the length of the operating devices.

A still further object of my invention is to provide supplemental means for varying the minimum height of the forward end of the spade elements.

Another object of my invention is to adapt the improved machine for mounting on a tractor of the usual construction and from which power can be obtained for operating the machine.

A still further object is to insure that the dirt will be moved without likelihood of being scattered.

Incidental to the last named object, it is intended to prevent the dirt from being thrown beyond the trench which is being filled.

A further object is to provide means for mechanically guiding the machine along the open trench.

Other objects of my invention will be clearly

2

apparent from the following description of the preferred embodiment of my invention.

This embodiment has been shown by way of example on the accompanying drawings in which—

Fig. 1 is a plan view of the improved machine for back-filling trenches;

Fig. 2 is vertical transverse section taken on line 2—2 of Fig. 1 and showing the spade elements and adjusting and operating means;

Fig. 3 is an elevation of the same elements from the trench side;

Fig. 4 is a similar elevation from the opposite side and

Fig. 5 is a transverse elevation of an alternative spade arrangement.

In order to illustrate the essential features of my invention, I have shown the improved machine for back-filling trenches as built into a tractor of usual construction. This tractor has a frame 1 mounted upon a wheeled underbody in which the gauge is sufficiently great to straddle the ridge of excavated dirt. This will bring the wheels on one side close to the open trench into which the dirt is to be replaced.

The tractor frame includes an operating platform 2 on which a workman may stand and control both the movement of the tractor, its direction of movement and the several operations carried out in back-filling the trench.

Under ordinary conditions of operation the several operations of advancing, filling and guiding are performed automatically without action by the workman. He merely supervises and adjusts for unevenness of the ground traversed.

An engine 3, specifically an internal combustion engine, is mounted in front of the platform 2. It has the usual means for propelling the tractor. It also is provided with a power take-off shaft 4 extending forwardly from the engine 3 to deliver power to the filling machine proper.

The shaft 4 is connected by means of clutch 5 to a belt-pulley 6, suitably journaled on a cross member of the tractor frame 1. Clutch 5 is operated by means of cone clutch 7, which in turn is shifted by means of lever 8 connected by rod 9 to a hand-lever 10 mounted above the operating platform 2. By this means, the operator is able to connect the filling machine to the power shaft 4 in setting the machine in operation.

A counter-shaft 11, also suitably journaled on the frame 1, has a belt pulley 12 at its forward end which is connected by means of drive belt 13 with the belt pulley 6.

The rear end of the counter-shaft is received

in a bevel-gear box 14. From this gear box, a drive shaft 15 runs transversely of the frame 1. It terminates at its free end in a gear box 16 which is suitably hung from the frame.

This gear box accommodates driving means 5 consisting of a worm and gear or two bevel-gears or the equivalent.

A crank shaft 17 is journaled transversely in the gearbox 16 and is operated by the gear combination of worm and gear, bevel-gears, or the like.

The forward end of the crankshaft 17 has a crank 18, while the crank 19 extends to the rear from the shaft 17. These cranks serve to support the forward ends of the spading elements.

The spading elements consist of a pair of bars 20 and 21. Each bar is substantially in a horizontal position at its lower limit of movement as will be described hereinafter.

The bars extend transversely of the tractor as shown in Fig. 1. Each bar has a series of inclined parallel rods depending from the bars. Each rod carries a spade or similar scooping blade 23 below the bars 20 and 21.

In normal operation, the bars 20 and 21 are suspended so that their motion is limited in the lower positions to a general horizontal plane parallel with the surface of the ground G in Fig. 2.

This limiting position is provided for by suspension means connecting the ends of the bars 20 and 21 with the tractor frame 1. In Fig. 2, the side bars of the tractor frame 1 are illustrated in section. They form supports for lateral brackets 24, 25. Brackets 24 extending laterally from the tractor on the side opposite the trench have a rockshaft 24' having pairs of pivoted bell-cranks 26, 26', 27 and 27'. The outer ends of the cranks 26, 26' have free swinging vertical links 28, 28', pivoted in bracket 29 to the rear end of the bar 20. In like manner, each bell-crank 27, 27' are connected by links 30, 30' to similar bracket 31 on the bar 21. The inner ends of the bell-cranks 26, 27 are connected to a shaft 32 which in turn is connected by means of a link 33 to a crank 34. This crank 34 is fixed on an adjustment wheel 35, mounted on the frame of the tractor in a manner not illustrated, but which will be obvious to one familiar with such structures. A worm shaft 36, carrying a worm 37 in mesh of the gear 35 is connected at its other end to a pair of bevel-gears 38. One of these bevel-gears 38 is mounted upon the forward end of a shaft 39. This shaft is journaled on the cross-members of the tractor frame 1 and at the rear has a hand-wheel 40. By adjustment of the hand-wheel 40, the position of arm 34 is adjusted and likewise the bell-cranks 26, 27 serve to lift or lower the rear ends of the bars 20 and 21.

Similar means is provided for adjusting the effective minimum heights of the forward ends of the bars 20 and 21. Bar 20 has a pivotal connection through pivot 41 to the crank 18 on the crankshaft 17. The gear box 16 in turn is suspended pivotally by means of a pair of links 42 and 43 pivoted in turn to bell-cranks 44 and 45, respectively. These bell-cranks, as shown in Fig. 3, are pivoted on a rockshaft 25' carried on brackets 25. Links 46, 47 are likewise pivoted on the rock shaft 25' and are connected by rods 48 to an arm 49 fixed on the shaft of the gear 35 (Fig. 2). A link 50 extends forwardly from the pivot point of the links 46 and 47 of rod 48 and between 44 and 45. This link 50 is slotted at 51 to receive a pin 52 which is carried on the rear

branches 53, 54 respectively of the laterally disposed bell-crank levers 44 and 45.

An adjustment screw 55 is threaded on the forward end of the link 50 and rests against the free end of one of the branches 53 and 54.

By this means, the branches 53 and 54 may be suspended lengthwise along the link 50.

Disregarding the adjustment of screw 55, any adjustment of the gear 35 will give equal adjustment to the bell-crank levers 26, 27, 53 and 54. Thus, the ends of the bars 20 and 21 are caused to rise and fall equally with respect to the horizontal plane. In this motion and due to the pivoted link 42 the gear box 16 remains at a constant distance from gear box 14, around which it moves radially.

In the event that the forward ends of the spade-bars are to be raised slightly out of the horizontal position, this can be accomplished by adjustment of the screw 55.

With the normal positions of the bars 20 and 21 provided for as above described, rotation of the crankshaft 17 causes the cranks 18 and 19 to rotate. This causes the forward ends of the bars and the series of spades to follow a circular path of movement, advancing in the lower half to push forward a portion of the dirt and retreating in the upper return movement free from the loose material.

25 This rotary movement of the forward ends of the bars becomes substantially a slight to-and-fro rocking at the rear ends by reason of the pivotal movement of links 28 and 30 around the upper pivot points.

30 In this way the ridge of material is gradually advanced step-by-step and thrown into the open trench, 56, Fig. 2.

35 As some of the loose material may be out of the path of the rear series of spades 23, that material may be lost. In order to prevent such material being pushed out of the normal path of movement, I have arranged a baffle 57 which is suspended by means of bell cranks 59 on a rock shaft 58' journaled on brackets 59 on the frame 1.

40 A suitable worm shaft 60 actuates a gear (not shown) on shaft 58' and allows the baffle 57 to be lifted and lowered as occasion may demand.

45 In this way, the loose material is prevented from scattering and in fact the baffle 57 provides a screed which levels off the surface of the ground after the dirt has been scooped into the trench returning any loose dirt to the path of movement of the spades.

50 It is also important that an abutment be provided on the far side of the open trench to throw back into the trench any dirt which is thrown beyond the trench. I have provided such an abutment 62, suspended from arms 63, 63 on a rock shaft 64. Rockshaft 64 is pivotally carried by brackets 65, 65, as shown in Fig. 1. A wheel 66 fastened on rockshaft 64 is connected by cable 67 to an adjustment wheel 68 mounted on the side of the tractor frame 1 by the operating platform 2. This permits the abutment 62 to be lifted or lowered into position close to the ground by the trench.

55 Means are also provided to effect automatic guiding of the machine along the open trench. The rockshaft 64 has fixed arms 69, 69 with a depending yoke 70 pivoted to the arms 69. The yoke 70 has a loose roller 71 journalled on it in a vertical plane. As the shaft 64 is rocked, the roller 71 is lowered into the trench and engages one side.

60 An extension 72 is fixed on the yoke 70 and has

a pivotal link 73 also pivoted to the slide 74 at the center of the front axle.

The slide 74 is carried in a curved track 75. Two reach rods 76, 76 extend in opposite directions from the slide 74. As the extension 72 is tilted by the yoke 70, the slide 74 moves to one or the other side and turns the front wheels into position to follow the trench accurately. When the machine is not engaged in back-filling a ditch but is to be transported, the usual steering is effected by the drag-link 80.

In some operating conditions, it is necessary to use greater power to drive the spade units. Thus, I have under such conditions modified the movement of each spade element so that a uniform circular motion is given to the spades throughout the length of the element. Such an arrangement has been shown in the modification illustrated in Fig. 5.

Here the belt pulley 12 is rotated by the drive belt 13 from shaft 6 (not illustrated). Power from the pulley 12 enters the gear box 14 and drives the shaft 15 and the crank shaft 17 in the manner already described.

In this arrangement, the gear box 16 is suspended by rigid arms (not illustrated) from the vehicle frame.

Leading from the gear box 14 in a direction opposite to the shaft 15 is a universal joint 17. This is conducted to a shaft 18 which enters a second gear box 19. Gear box 19 is suspended by a fixed arm (not illustrated) from the vehicle frame.

The second gear box 19 has an additional crank shaft 17 and opposed cranks. One crank 18 has the same angular position as crank 18 on the first described shaft 17 while an opposite crank is directed oppositely in the same direction as crank 19 on the first described shaft 17.

The bars 20 and 21 are journaled on the cranks 18, 18 and 19, 19 respectively. It will thus be apparent that bars 20 and 21 are maintained parallel and rotate in the same direction but in opposite phases.

This gives each spade 23 the same stroke and provides a uniform transverse movement of the dirt.

By means of the machine thus described, I provide for efficient transverse movement of the dirt from a ridge or pile into an already excavated trench. The movement of the dirt may be accelerated in quantity as it approaches the trench or is uniformly advanced as in the example last described.

Means are provided to prevent lateral scattering of the material and its delivery into the trench without being thrown beyond the trench.

By suitable correlation of movement, the vehicle is advanced as the ridge of dirt is returned

to the trench. In this movement, the forward wheels of the vehicle are controlled so that they travel parallel to the trench and are guided by the latter. In this way a minimum of attention is required on the part of the operator.

The preferred form of my invention has been described in detail but may be varied in respect to arrangement of parts, materials and proportions without departing from the scope of the invention as defined in the following claims.

What I claim is:

1. In a portable machine for back-filling trenches, a frame, a pair of bars, a series of spades mounted on each bar, a rock-shaft on one side of the frame, two pairs of bell-crank levers on the shaft, two links pivotally suspending one end of each bar independently from one pair of bell-crank levers, a driving shaft, bearing means therefore, a second rock-shaft on the opposite side of the frame, a pair of bell-crank levers on said second shaft, two links pivotally suspending the bearing means from said last named pair of bell-crank levers, a common adjusting gear intermediate the sides of the frame, links connecting the gear with each pair of levers, a pair of opposed cranks on the drive-shaft and a pivotal connection between each crank and the adjacent end of one of said bars.

2. In a portable machine for back-filling trenches, a frame, a pair of bars, a series of spades mounted on each bar, a rock-shaft on one side of the frame, two pairs of bell-crank levers on the shaft, two links pivotally suspending one end of each bar independently from one pair of bell-crank levers, a common adjusting gear intermediate the sides of the frame, a link connecting the gear with said pairs of bell-crank levers, a driving shaft, a pair of opposed cranks thereon, a pivotal connection between each crank and the adjacent end of one of said bars, bearing means for the drive-shaft, a second rock-shaft on the second side of the frame, a pair of bell-crank levers on the rock-shaft, two links pivotally suspending said driving shaft bearing means from the said last named bell-crank levers, and adjustable linkage connecting the common adjusting gear with said last named bell-crank levers.
